ELECTRON DEVICE

Fred. B. MacLaren, Clifton, N. J., assignor, by
mesne assignments, to Revelation Patents
Holding Company, a corporation of Delaware

Application December 16, 1929, Serial No. 414,287

26 Claims. (Cl. 250—27.5)

This invention relates to electron devices and particularly to such devices as are used as amplifiers to increase electrical impulses as in a radio receiving set or in sound motion picture work.

In electron devices now in use for this type of work the power output of the device is somewhat limited. Also in order to get undistorted output with such devices it is necessary to apply a negative bias to the control electrode thereof.

It is therefore, one of the objects of the invention to provide a thermionic tube which has a large power output.

Another object of the invention is to provide a thermionic tube in which the positive swing of the grid may be utilized to produce undistorted amplification.

Another object of the invention is to provide a thermionic tube which will give undistorted output without grid bias.

Another object of the invention is to provide a thermionic tube with an auxiliary grid-cathode unit therein not connected with any elements of the tube or with the terminals thereof.

Other objects of the invention and objects relating to the method of constructing and assembling the various parts and connecting the parts together will be apparent as the description of the invention proceeds.

Several embodiments of the invention have been illustrated in the accompanying sheets of drawings in which:

Fig. 1 is a diagrammatical view of the tube and the circuit therefor;

Fig. 2 is a sectional front elevation of one embodiment of the invention which may be preferred;

Fig. 3 is a plan view of the elements shown in Fig. 2;

Fig. 4 is a sectional front elevation of another embodiment of the invention;

Fig. 5 is a plan view of another embodiment of the invention;

Fig. 6 is a plan view of still another embodiment of the invention;

Fig. 7 is a diagram of a modified circuit for the invention; and

Figs. 8 and 9 are diagrammatical views of the invention used in connection with a four terminal base.

In general the invention comprises a thermionic tube which has two cathodes and two grids, one of each being an auxiliary electrode, and a single anode. One of the grids acts as an input grid similarly to the grid of any ordinary thermionic tube and one of the cathodes acts as

an ordinary cathode. The anode is adapted to be connected to the output circuit similarly to the ordinary tube. The auxiliary cathode is connected to the auxiliary grid so that these two parts are electrically connected together but are entirely independent of any of the other elements. The first grid may be mounted adjacent the auxiliary cathode while the auxiliary grid may be mounted adjacent the first cathode, the anode surrounding all of the electrodes.

Referring more specifically to Fig. 1 of the drawings in which the circuit diagram of the construction is shown an envelope 10 has within it a grid 11, an anode 12, and a cathode 13. These three elements operate somewhat similar to the grid, anode, and cathode of an ordinary electron tube, but the action is varied by the insertion of an auxiliary cathode and grid. The auxiliary cathode 14 emits electrons to the anode 12 and this electron stream is controlled by the grid 11. An auxiliary grid 15 is connected directly to the auxiliary cathode 14 and controls the electron emission from the cathode 13 to the anode 12. A heater 16 may be provided to heat the cathode 14 and a heater 17 may be provided to heat the cathode 13 and these heaters 15 may be arranged in parallel, if desired, or in series, or a single heater may be used for both as will be described hereinafter.

Two wires 18 may lead out of the envelope from the filament and connect to the secondary 19 of a transformer 20, the primary 21 of which is connected to an alternating current power source. The grid 11 may be connected by means of a wire 22 to the secondary of an input transformer 24, as is customary in the art, and the anode 12 may be connected by means of a wire 25 to the primary 26 of an output transformer 27. The other end of the secondary 23 of the input transformer 24 may be connected by means of a wire 23a to the negative of a B battery 28 while the positive side of the B battery may be connected to the other end of the primary 26 of the output transformer 27. The cathode 13 may be connected by means of the wire 29 to the wire 23a which is connected to the negative side of the B battery and a condenser 30 may be connected across the B battery to permit the feedback from the anode in a manner well-known in the art.

I believe the theory of operation of the device as just described may be somewhat as follows: Signals impressed upon the input of the transformer 24 cause a variation in the secondary 23 and, therefore, a potential variation of the

5

50

55

grid 11. The grid 11 influences the electron emission from the cathode 14 and as this cathode is directly connected to the grid 15 the latter controls the output of the tube as it controls the electron emission between the cathode 13 and the anode 12. As described in my Patent No. 1,959,540, issued May 22, 1934, when the grid 15 swings negatively due to a negative potential on the grid 11 which is transferred to the grid 15 by virtue of the change in the electron stream from the cathode 14 which is connected to the grid 15, the tube will amplify undistorted signals similarly to any electron tube now in use. However, when the grid 15 becomes positive due to a positive swing of the grid 11, electrons which are emitted to the grid 15 from the cathode 13 cause a current to flow between the grid 15 and the cathode 14 in the same direction which is normally taken by the current caused by the electron emission from the cathode 14 to the anode 12. As the cathode 14 is connected to the grid 15 it is more positive than the cathode 13 and, as the latter is connected through the outside circuit to the grid 11, the cathode 14 is more positive than the grid 11, and hence even though the grid 11 is positive no current will flow in the input circuit through the secondary 23 of the transformer 24. Therefore, when the grid 11 is negative no current will flow in the input circuit, as is well-known in the art, and when the grid 11 is positive no current will flow due to the auxiliary cathode 14 and grid 15.

Thus the tube of the present invention amplifies without distortion as the grid swings between positive and negative. While this explanation of the theory of operation of the invention may not be correct I have been led to believe that it works in this manner. In any case the tube amplifies and gives a greater power output than the average tubes now in use and the swing of the potential on the grid need not be limited as by a negative grid bias.

In Figs. 2 and 3 I have shown one way in which the various elements of the tube may be mounted. An anode 31 corresponding to the anode 12 of Fig. 1 may be formed of a flattened tube of sheet nickel or other metal with the other elements supported within it. A grid 32 corresponding to the grid 11 of Fig. 1 is formed of a helical coil of molybdenum or other wire positioned within the anode, extending longitudinally thereof, and spaced from the walls thereof. Inside of the grid 32 I provide a cathode 33 which is preferably a cylinder of nickel or other desirable metal coated with an electron emitting material. This cathode is connected by means of a wire 34 to a second grid 35 which is arranged parallel to the grid 32 and comprises a similar coil mounted with the anode 31 as clearly indicated in Figs. 2 and 3. Within the grid 35 I provide a cathode 36 which may be similar to the cathode 33 already described.

The cathodes 33 and 36 may be heated in any desired manner but in the present instance I have shown two rods 37 and 38 of insulating material within the cathodes 33 and 36 respectively, each of these rods having a hole extending longitudinally through the center thereof through which a filament 39 may pass. A press 40 may be provided in the device and the elements may all be supported upon the press in any desirable manner, the electrical connections for the various elements being sealed therein. Thus the anode 31 is provided with an electrical connection 41, the grid 32 with an electrical connection 42, the

cathode 36 with an electrical connection 43 all of which connections are sealed in the press and the two ends of the filament 39 may also be sealed in the press as indicated. This makes five connections so that the tube may be used to replace the five terminal tube now in use. The operation of this device is similar to what has already been explained in connection with Fig. 1.

In Fig. 4 I have shown another embodiment of the invention in which a cylindrical anode 44 has within it a pair of helical grids 45 and 46 spaced apart longitudinally as indicated. The grid 45 corresponds to the grid 11 in Fig. 1 and may be connected to the external circuit by means of a lead 47. Within the grids 45 and 46 I provide cathodes 48 and 49 respectively having a length approximately equal to the length of the grid in each case. The cathode 48 corresponds to the cathode 14 of Fig. 1 and may be connected to the grid 46 by means of wires 50 as indicated. The cathode 49 may be connected to the external circuit by means of the wire 51. Also the anode 44 may be connected to the external circuit by means of the wire 52.

In order to heat the cathodes 48 and 49 I provide an insulating rod 53 which extends completely through both of the cathodes, longitudinally thereof, and is provided with a pair of holes extending axially therethrough. A hairpin filament 54 is provided with one leg extending through one hole and the other leg through the other in the insulator the end of each leg being connected to the external circuit by a plurality of wires 55. The operation of this construction is similar to what has already been described.

In Fig. 5 I have shown a still further modification of the construction shown in the preceding figures. A cathode 56 formed of a tube of nickel corresponds to the cathode 14 of Fig. 1 and is surrounded by a coil 57 forming the grid which corresponds to the grid 11 of Fig. 1. Around this grid is positioned an anode 58 which is preferably in the form of a tube and corresponds to the anode 12 of Fig. 1. A second anode 59 considerably larger in diameter than the anode 58 is placed around the latter but is electrically connected to it by means of the wire 60 thus making a single electrical anode out of the two cylindrical anodes 58 and 59. Between these two anodes I preferably position a plurality of cathodes 61 each of which is surrounded by a grid 62. All of the cathodes 61 are connected together as by means of a wire 63 and these cathodes correspond to the cathode 13 of Fig. 1. All of the grids 62 are also connected to the cathode 56 as by wires 64 and these grids correspond to the grid 15 of Fig. 1.

In order to heat the cathodes 56 and 61 I provide insulating sleeves or rods through which the hairpin filaments are positioned as was described in connection with Fig. 4 and these filaments may be connected in parallel or in series as desired. Any desired number of the cathodes 61 and grids 62 may be used but I prefer to use six as indicated in the figures. The same theory of operation as has been described in connection with the other figures obtains in this case.

In Fig. 6 I have illustrated a still further embodiment of the invention. In this case a cylindrical cathode 65 is provided with a suitable heating means as the filament 66 and is surrounded by a helical coil of wire 67. This coil of wire is a combined cathode and grid taking the place of the cathode 14 and the grid 15 of Fig. 1.

Around this coil 67 I provide another helical coil 68 which is the grid corresponding to the grid 11 of Fig. 1 and a cylindrical anode 69 is provided surrounding the grid 68. In this case the combined cathode and grid 67 receives enough heat from the first cathode 65 to cause it to emit electrons giving the same effect as the construction already described. I prefer to coat the combined cathode and grid 67 with some material which will emit electrons at a lower temperature than is normally used as it depends for heat upon the first cathode 65 and will therefore, necessarily remain at a temperature lower than the cathode 65. Hence, if it is provided with a coating which is active at lower temperatures it will function similarly to the cathode 14 of Fig. 1. I prefer to use caesium as a coating material for this purpose.

The mesh of the combined grid and cathode is preferably much finer than the mesh of the outer grid so that the amplification constant of the outer grid is lower than the inner one.

I have found that a positive bias on the input grid is a desirable addition to the invention. As the input grid is nominally negative the positive bias will offset part of the negative bias already there and let the grid function over the straight line portion of the grid voltage-plate current characteristic curve. Such a grid bias may be made by means of the resistance 11 shown in Fig. 7, or a battery may be inserted in the transformer cathode lead with its positive terminal towards the grid 11.

The tube can also be mounted upon a four terminal base by connecting the cathode 13 directly to a portion of the heating circuit inside of the base tube as indicated in Fig. 8 or, if desired, to the mid-point of the filament, or a resistance 72 (Fig. 9) may be connected across the heater leads inside of the base and the cathode terminal may be connected to the mid-point of this resistance. This construction has the advantage that no plate current flows through the filament and, therefore, a tendency to overheat the filament is avoided.

The tube of the invention has more power output because the output impedance is very low and a very high amplification constant may be used without increasing the impedance greatly. The limiting factor in the operation of the tube is the high temperature of the anode because of high plate current. This can however, be brought to a reasonable amount by increasing the amplification constant and letting the plate current swing by a large amount.

While the invention has been shown and described in connection with an alternating current source of heater energy it is evident that the tube will also operate on direct current or any other means of heating the cathode may be resorted to. The tube may be also used for amplifying either radio or audio frequency currents and also as an oscillator or modulator, or detector.

It will be evident from the above that I have provided an electron tube having four or five terminals so that it may be substituted for the standard alternating current tube now in use which will produce a greater power output as it is not necessary to limit the swing of the grid potential in the incoming circuit.

Modifications of the invention may be resorted to without departing from the spirit thereof, and I do not therefore, desire to limit the invention to what has been shown and described except as such limitations occur in the appended claims.

1. An electron device comprising a press, a tubular anode positioned above said press, a wire sealed in said press and connected to said anode, a tubular grid positioned within said anode, a wire sealed in said press and connected to said grid, a tubular cathode within said grid, a second tubular grid within said anode and spaced from said first grid, a wire connecting said second grid directly with said cathode, a second cathode within said second grid, a wire sealed in said press and connected to said second cathode, and a heating filament adjacent said cathodes to heat them to an electron emitting temperature. 10

2. An electron device comprising a grid, a cathode connected directly to said grid, a second grid adapted to influence the electron emission from said cathode, a second cathode adjacent said first grid whereby the electron emission thereof is influenced by said first grid, and an anode adapted to receive electron emission from both of said cathodes. 15

3. An electron device comprising a cathode, a tubular grid surrounding said cathode, a tubular anode surrounding said grid, a plurality of cathodes positioned adjacent the outer surface of said tubular anode, a tubular grid surrounding each of said tubular cathodes, said grids being all connected to said first mentioned cathode, and a second tubular anode surrounding said plurality of cathodes and grids and connected to said first mentioned anode. 25

4. An electron device comprising an electron emitting cathode, an insulated coil of wire surrounding said cathode and acting as a combined secondary cathode and grid, a tubular grid surrounding said coil, and a tubular anode surrounding said grid to receive the electrons emitted by both cathodes. 35

5. An electron device comprising a cathode, an insulated coil of wire surrounding said cathode and acting as a combined secondary cathode and grid, a coating on said coil adapted to emit electrons at a lower temperature than said cathode, a tubular grid surrounding said coil, and a tubular anode surrounding said grid. 40

6. An electron device comprising a tubular anode, a tubular grid within said anode, a tubular cathode within said grid, a second tubular grid within said anode and spaced from said first grid, said cathode and second grid being directly connected together electrically, a second cathode within said second grid, and means to heat said cathodes. 45

7. An electron device comprising a tubular anode, two tubular grids within said anode and spaced therefrom and from each other, and a tubular cathode within each of said grids, one of said cathodes being directly connected to one of said grids but insulated from the other elements. 55

8. An electron device comprising, a tubular anode, a pair of tubular grids mounted within said anode and longitudinally spaced from each other, and a pair of cathodes, one within each grid, one of said cathodes being directly connected to one of said grids. 60

9. An electron device comprising a tubular anode, a second tubular anode within said first anode and spaced therefrom and connected electrically thereto, a cathode within said second anode, a grid between said second anode and cathode, a plurality of cathodes positioned between said anodes, and a plurality of grids, one adjacent each of said last mentioned cathodes, said last mentioned grids being connected together and to said first mentioned cathode, and 70

75

- said cathodes between said anodes being connected together.
10. An electron discharge tube comprising an evacuated envelope, a first cathode, a grid positioned to influence the electron emission from said cathode, a second cathode, a grid positioned to influence the electron emission from said second cathode, said second grid being directly connected to said first cathode, and an anode for 10 each of said cathodes.
11. An electron discharge tube comprising an evacuated envelope, a first cathode, a grid positioned to influence the electron emission from said cathode, a second cathode, a grid positioned 15 to influence the electron emission from said second cathode, said second grid being directly connected to said first cathode, an anode positioned to receive electrons emitted from said first cathode, and an anode positioned to receive the electrons emitted from said second cathode.
12. An electron discharge device according to claim 11 in which the said anodes are electrically connected.
13. An electron discharge device comprising an 25 evacuated envelope, a first cathode, a grid positioned to influence the electron emission from said cathode, a second cathode, a grid positioned to influence the electron emission from said second cathode, anodes for said grids, and a direct 30 metallic connection between the said first mentioned cathode and the second mentioned grid.
14. A vacuum tube comprising an envelope containing a cathode, a grid and a plate element, another cathode, grid and plate element, a heater 35 element for indirectly heating said cathodes, said second mentioned grid being directly connected with the first mentioned cathode.
15. A vacuum tube comprising an envelope containing a cathode, a grid and a plate element, 40 another cathode, grid and plate element, a heater element for indirectly heating said cathodes, said second mentioned grid being directly connected with the first mentioned cathode, and means for electrically insulating the first mentioned cathode 45 from the second mentioned cathode.
16. A vacuum tube comprising an envelope containing a cathode, a grid and a plate element, another cathode, grid and plate element, a heater element for indirectly heating said cathodes, the 50 first mentioned grid offering a higher impedance than the second mentioned grid, said second mentioned grid being directly connected with the first mentioned cathode, and means for electrically insulating the first mentioned cathode from 55 the second mentioned cathode.
17. An electron discharge device comprising an envelope containing a plurality of triode units, each unit consisting of an electron emission element, a grid element and a plate element, the 60 grid element of one unit being connected to the electron emission element of another unit.
18. An electron discharge device comprising an envelope containing a plurality of triode units, each unit consisting of an electron emis-
- sion element, a grid element and a plate element, an electron emission element heater, the grid element of one unit being connected to the electron emission element of another unit.
19. An electron discharge device comprising an envelope containing a plurality of triode units, each unit consisting of an electron emitter, a grid and a plate, said electron emitters being insulated from each other, the grid of one triode being connected to the electron emitter of another triode unit.
20. An electron discharge device comprising an envelope containing a plurality of triode units, each unit consisting of an electron emitter, a grid and a plate, said electron emitters being insulated from each other, an electron emitter element heater, the grid of one triode unit being connected to the electron emitter of another triode unit.
21. An electron discharge device comprising a first-electron emitting cathode, a second electron emitting cathode, a first grid positioned to influence the electron emission from said first cathode, a second grid positioned to influence the electron emission from said second cathode, said second cathode and first grid adapted to have signal impulses impressed directly thereon, said first cathode and second grid being directly connected to each other.
22. An electron discharge device comprising a first electron emitting cathode, a second electron emitting cathode, a first grid positioned to influence electron emission from said first cathode, a second grid positioned to influence electron emission from said second cathode, said second cathode and said first grid forming the terminals of an input circuit for said device, said first cathode and said second grid being connected together to provide a pair of serial space paths inside said device between said second cathode and said first grid.
23. An electron device comprising an electron emitting cathode, means to heat said cathode, a mesh of wire positioned to receive heat from said cathode but not metallically connected to said cathode, the surface of said mesh being treated to emit electrons, and said mesh acting as a combined secondary cathode and grid to influence emission from said cathode, another grid positioned to influence the electron emission from said secondary cathode, and an anode positioned to receive electrons from said cathode and said secondary cathode.
24. An electron discharge device according to claim 22 in which a single anode is positioned to receive electrons from the mentioned cathodes.
25. An electron discharge device according to claim 22 wherein each grid is provided with a separate anode.
26. An electron discharge device according to claim 22 in which each grid is provided with a separate tubular anode surrounding the same.

FRED. B. MACLAREN.
